SPARK ARRESTER

Application filed July 9, 1927, Serial No. 204,574, and in Switzerland September 4, 1926.

This invention relates to internal combustion engines and has for its object to provide an improved system for conducting the exhaust gases into the atmosphere whereby no sparks are carried out with the gases.

According to this invention the exhaust gases are caused to pass through a device or chamber in which they are made to whirl on their way from the engine cylinders to the atmosphere, any particles of solid matter being completely burnt before they leave this chamber. The exhaust pipes from one or more internal combustion engines are arranged to open into a common receiving chamber, from the upper part of which a connecting pipe leads to the whirl-imparting chamber, which the gases enter tangentially. If desired a silencer may be provided in the length of each exhaust pipe between the engine and the receiving chamber. The exhaust gases leave the whirl-imparting chamber tangentially and enter an exhaust pipe which is preferably of larger cross-section than the inlet pipe, the open end of this pipe extending about mid-way down the length of the chamber. Conveniently fixed or adjustable guide vanes may be provided between the receiving chamber and the whirl-imparting chamber by means of which the stream of gases is directed tangentially into the latter, and in the preferred construction a helical conduit is formed within the whirl-imparting chamber between the inlet and outlet ports thereof.

The invention may be carried into practice in various ways but two constructions by way of example are illustrated in the accompanying drawings in which

Figure 1 shows one arrangement in cross-section on the line *a—a* of Figure 2,

Figure 2 is a plan, and

Figure 3 is a plan of part of an alternative construction according to the invention in which guide vanes are provided between the receiving chamber and the whirl-imparting chamber.

In the construction illustrated in Figures 1 and 2 the exhaust gases from one or more engines pass into pipes 4, 5 and 6, from which they enter a common receiving chamber 3.

Where desirable, exhaust silencers or mufflers, may be inserted in the several exhaust conduits leading to the receiving chamber. A smoke flue 7 is also provided which passes directly through the chamber 3 into the atmosphere. Although not necessary where only the exhaust gases of one or more internal combustion engines are to be handled, such a flue is used to discharge the smoke gases of a furnace in instances where the device of the invention is employed as a common exhaust for an entire plant consisting of one or more furnaces and one or more internal combustion engines. The exhaust gases pass from the receiving chamber tangentially by a port 10 into a whirl-imparting chamber 2 through a helically shaped conduit 9 extending down into the chamber. The outlet end 11 of the helical conduit is so disposed that the gases leave this conduit in a direction which is tangential with respect to the chamber 2 and pass out through a centrally arranged exhaust pipe 8, thus escaping to the atmosphere by way of the opening 14. The exhaust pipe 8 should be made as short as possible in order to avoid any undue suction effect and the cross-section of the outlet opening 14 is made greater than that of the inlet 10. The lower end of the whirl-imparting chamber 2 is formed conical and has a flanged opening 13 to which may be connected a pipe (not shown) leading to a water tank, the opening 13 being used for the purpose of withdrawing solid residues from the chamber 2.

In the alternative construction illustrated in Figure 3 guide vanes 16 are provided between the receiving chamber 3 and the whirl-imparting chamber 2 in order to direct the current of gases tangentially and a ring 17 to which the guide vanes 16 are operatively connected is provided for the purpose of varying the angle of the vanes, and thus the angle at which the current of gases is directed into the chamber 2, the arrangement being similar to that employed in water turbines. As shown in the figure, guide-vanes 16 have been provided instead of the helical area 12, represented in Fig. 1, for imparting a whirling motion to the current of exhaust gases.

Although the modes of construction have been shown separately it is to be understood that the helical area 12 and the guide-vanes 16 may also be used simultaneously.

5 The operation of the apparatus is as follows.

The gases flowing from the engines through the exhaust pipes 4, 5 and 6 into the receiving chamber 3 enter the chamber 2 through the inlet 10 and by means of the helical partition 12 forming one wall of the conduit 9 or, alternatively, by means of the guide vanes 16 have a whirling motion imparted to them. The exhaust gases are thus drawn out towards the conical point 13 and it is not until they nearly reach this point 13 that they begin to ascend towards the pipe 8 through which they pass out into the atmosphere.

The construction and arrangement above described has the great advantage that no sparks can pass out of the pipe 8, so that the apparatus acts as a spark arrester. This effect is obtained not only by means of the helical conduit 9 but also by means of the circular movement of the gases towards the conical point 13 which is set up, and by the longer period thus obtained for the combustion of any solid matter, as well as by the reduction of velocity caused by the suitably dimensioned cross-sections of the inlet and outlet openings. The solid glowing particles which are almost always present in the exhaust gases are retained within the chamber and carried round in a circle by centrifugal force until they are completely burnt. In this way the resistance to the flow of the gases which is set up by such particles adhering to the sides of the exhaust pipe is eliminated.

I claim:

40 1. An exhaust device of the type described, comprising an exhaust gas receiving chamber, a whirl-imparting chamber having a closed funnel shaped lower end and an inlet opening near its upper end communicating with said receiving chamber, a discharge conduit extending downwardly into said whirl-imparting chamber from the upper end thereof, said conduit having a greater cross-sectional area than said inlet-opening, and means for directing a current of exhaust gases from said receiving chamber in a helically downward direction through said whirl-imparting chamber toward said funnel shaped lower end and up through said conduit, whereby the solid glowing particles entrained in said exhaust gases are maintained in constant whirling motion and not discharged through said conduit until they have been reduced to a completely burned and pulverized state.

60 2. A spark arrester device according to claim 1, characterized by the provision of means for directing exhaust gases from the receiving chamber downward through a whirl imparting chamber and upward thence through the discharge conduit, said means

comprising a helical vane extending around the discharge conduit and forming an annular helical passage communicating with the inlet opening and terminating in the lower portion of the whirl-imparting chamber.

70 3. A device according to claim 1, characterized by the provision of a plurality of guide vanes adjacent the inlet opening for directing the current of exhaust gases.

75 4. A device according to claim 1, characterized by the provision of a plurality of adjustable guide vanes adjacent the inlet opening for variably directing the current of exhaust gases.

80 In testimony whereof I have affixed my signature.

SIMON GERARDUS VISKER.
